United States Patent Office

Des. 220,947
Patented June 22, 1971

220,947

BUILDING STRUCTURE

Guy A. Bartoli, 2914-C St. Mark Road,
Winston-Salem, N.C. 27103

Filed June 1, 1970, Ser. No. 23,246

Term of patent 14 years

Int. Cl. D25—04

U.S. Cl. D13—1

FIG. 4FIG. 5

FIG. 1 is an elevational view of a building structure embodying the novel design of the present invention;

FIG. 2 is an elevational view of the same taken from the opposite side and at a radial angle of about 160° from that of FIG. 1;

FIG. 3 is a plan view of the same in reduced scale;

FIG. 4 is an isometric view looking down and taken from the radial angle of FIG. 1;

FIG. 5 is an isometric view looking up and taken from the radial angle of FIG. 2.

I claim:

The ornamental design for a building structure, substantially as shown.
